UNITED STATES PATENT OFFICE.

EDWARD JESCHKE, OF BELLEVUE, OHIO, ASSIGNOR TO THE JESCHKE MANUFACTURING COMPANY, OF BELLEVUE, OHIO, A CORPORATION OF OHIO.

DITCHING-MACHINE.

1,028,218.

Specification of Letters Patent. Patented June 4, 1912.

Application filed March 20, 1911. Serial No. 615,474.

To all whom it may concern:

Be it known that I, EDWARD JESCHKE, a citizen of the United States, and a resident of Bellevue, county of Huron, and State of Ohio, have invented a new and useful Improvement in Ditching-Machines, of which the following is a specification, the principle of the invention being herein explained and the best mode in which I have contemplated 10 applying that principle, so as to distinguish it from other inventions.

My invention relates to what are known as ditching machines, and the general object of the invention is the provision of a 15 machine of this class which will be characterized by extreme simplicity, so that it may be economically manufactured and easily maintained in working order.

To the accomplishment of the foregoing 20 and related ends, said invention, then, consists of the means hereinafter fully described and particularly pointed out in claims.

The annexed drawing and the following 25 description set forth in detail certain mechanism embodying the invention, such disclosed means constituting, however, but one of various mechanical forms in which the principle of the invention may be used.

30 In said annexed drawing:—Figure 1 is a side elevation of a machine embodying my invention, and Figs. 2 and 3 are cross-sections illustrating a ditch being dug by my improved machine, the two figures showing 35 two different stages of operation.

The machine comprises primarily, a suitable frame 1, provided with means whereby it may be pulled, and also provided with a suitable seat for a driver. Adjustably secured to the frame are two oppositely disposed knives 2, these knives being substantially vertically disposed and bending inwardly at their lower ends, as clearly shown in Fig. 3. In advance of the knives 2, a 40 cutter 3 is secured to the frame 1 and the cutter 3 is made of substantially U-shape, and of less width than the distance between the two vertical knives 2. A convenient manner of providing for the adjustment of 45 knives 2, and cutter 3, is to pivotally secure to the frame 1, a plate 4 on each side of the frame, and then attach the knives 2 and cutter 3 to the plates 4, the plates being provided with ridges bearing against the edges 50 of the knives and cutter, as clearly shown

in Fig. 1. The plates 4, are pivoted to the frame 1 on a bolt 5, which also serves to secure the cutter 3 to the plates; the plates 4 are provided at their rear ends with slots 6, which are engaged by bolts 7, extending 60 into the frame 1. Obviously, therefore, the plates 4, carrying the knives and cutter, may be held rigidly by means of bolts 7, in any desired position about the pivotal axis. In order to render the structure still more 65 rigid, rods 8, are pivoted to two sides of the cutter 3, and their forward ends are secured to the frame 1, by bolts 10, a series of holes 9, providing for adjustment of the 70 rods 8.

A handle 11, is pivoted to the frame 1, and its height may be varied by means of a rod 12, having a plurality of holes 13, a selected one of which is engaged by a bolt 14, extending through the handle. A wheel, 75 15, is secured to the lower end of a rod 16, which is vertically slidable through a retainer 17, secured to the frame 1, and a bolt 18 provides for securing the wheel rigidly 80 in any desired position.

In operation, the machine is usually drawn by a horse, and the rear end of the machine is manually depressed by an operator, by means of the handle. As the machine progresses, the U-shaped cutter severs a central 85 portion 19, from the ditch being dug, and obviously because of the shape of the cutter, this central portion is severed at an angle to a horizontal plane. The cutter is immediately followed by the knives, which sever 90 the portions at the sides of the cutter. Because the cutter has previously severed the angular central portion of dirt, the knives will complete the cutting operation much 95 more easily, for the side portions will force the central severed portion upwardly between them. In this manner, the excavating of the ditch is rendered much easier than where such central portion is not first 100 severed. After the machine has thus operated through any desired distance, it is necessary to remove the severed dirt by hand. After this has been done, the machine is drawn through the ditch a second time, and 105 the operations are continued until the desired depth has been obtained.

The machine has been made adjustable in all necessary ways, in order to accommodate the machine to various depths below the surface. The cutter and knives may be quickly 110

adjusted to different depths, and the wheel and handle may be correspondingly adjusted, so that they will coöperate with the knives and cutter no matter at what depth 5 the machine is operated.

Other modes of applying the principle of my invention may be employed instead of the one explained, change being made as regards the mechanism herein disclosed provided the means stated by any of the following claims or the equivalent of such stated means be employed.

I therefore particularly point out and distinctly claim as my invention:—

15 1. In a machine of the class described, the combination of a frame, a wheel depending from said frame near the front thereof, two plates secured on opposite sides of said frame and pivoted on an axis extending transversely of the frame, two substantially vertically disposed knives secured to the respective plates and bent inwardly at their lower ends, and a U-shaped cutter secured to said plates in advance of said knives, said 20 knives and cutter depending from said frame near the rear thereof and being designed to support the rear end of said frame.

25 2. In a machine of the class described, the combination of a frame, a wheel depending from said frame near the front thereof, two plates secured on opposite sides of said

frame and pivoted on an axis extending transversely of the frame, said plates being slotted at their free ends, bolts secured to said frame and engaging said 35 slots, two substantially vertically disposed knives secured to the respective plates and bent inwardly at their lower ends, and a U-shaped cutter secured to said plates in advance of said knives, said knives 40 and cutter depending from said frame near the rear thereof, and being designed to support the rear end of said frame.

3. In a machine of the class described, the combination of a frame, two plates secured 45 on opposite sides thereof and pivoted on an axis extending transversely of the frame, said plates being slotted at their free ends, bolts secured to said frame and engaging said 50 slots, two substantially vertically disposed knives secured to the respective plates and bent inwardly at their lower ends, a U-shaped cutter secured to said plates in advance of said knives, and two bars secured to the respective sides of said cutter and 55 adjustably secured to said frame.

Signed by me this 16 day of March, 1911.

EDWARD JESCHKE.
